UNITED STATES PATENT OFFICE.

WILLIAM S. HAMM, OF HUBBARD WOODS, ILLINOIS, ASSIGNOR TO THE ADAMS & WEST-LAKE COMPANY, OF CHICAGO, ILLINOIS, A CORPORATION OF ILLINOIS.

BAND-FEEDING DEVICE.

1,276,906.

Specification of Letters Patent.

Patented Aug. 27, 1918.

Application filed April 24, 1916. Serial No. 93,167.

To all whom it may concern:

Be it known that I, WILLIAM S. HAMM, a citizen of the United States, and resident of Hubbard Woods, county of Cook, and State of Illinois, have invented certain new and useful Improvements in Band-Feeding Devices, of which the following is a specification, and which are illustrated in the accompanying drawings, forming a part thereof.

The invention relates to devices for feeding sheet metal bands to the work to which they are to be applied; its particular object being to secure a high degree of efficiency.

One embodiment of the invention is hereinafter described, and is illustrated in the accompanying drawings in which—

Figure 1 is a plan view of the device;

Fig. 2 is a view of one of the bands upon which it is adapted to operate;

Figs. 3 and 4 are sectional views, respectively, on the lines 3—3 and 4—4 of Fig. 1;

Fig. 5 is a side view of the device, some parts being broken away;

Fig. 6 is a detail side view of the feeder;

Figs. 7 and 8 are detail sectional views taken, respectively, on the lines 7—7 and 8—8 of Fig. 6; and

Fig. 9 is a detail plan view of the feeder.

The device comprises a bed plate 10, which

may be mounted upon legs, as 11, 11, which, as shown, are adapted to be attached to a work-bench by means of screws. To the upper surface of the bed 10 are secured a

pair of opposed guides 12, 12, between which

the bands 13 are placed, resting upon one edge on the bed 10. A follower 14 is mounted upon the bed 10, and is slidable between the guides 12, 12, for advancing the bands

to the ways through which they are to be fed one at a time. The follower may be advanced by any suitable means. For this purpose there is shown a plurality of cords or

cables 15, attached to suitable lugs 16 depend-

ing from the follower and running in chan-

nels 17 in the bed 10, each of these cords or

cables running over a sheave 18 journaled in an aperture 19 in the bed, a weight 20 being

attached to its end.

The follower 14 is provided with a handle 21, by means of which it may be readily retracted for the purpose of refilling the device with bands, and may be held in its retracted position by means of a thumb latch

22, engageable with a stop block 23 at the 55 rear edge of the bed.

A pair of bars 24, 25, arranged longitudinally of the bed and rigidly secured thereto, limit the advance movement of the mass of bands and form a slideway along which they 60 may be successively fed. The upper bar 24 is provided on its front face with lips 26, having their lower faces beveled, as shown, for the purpose of insuring the accurate alining of the bands as they are fed. 65

The feeder comprises a block 27, slidable between the rear faces of the bars 24, 25, and a longitudinal guide-bar 28 fixed to the bed 10. The block 27 is provided with a suitable handle 29, by means of which it may be 70 conveniently reciprocated, and it is also provided with lateral flanges 30, 31, running, respectively, in a longitudinal channel 32 formed in the inner face of the guide-bar 28 and in a space between the bars 24, 25. 75

Pivoted within a transverse aperture in the block 27, and projecting laterally beyond both of its faces, is a dog 33, the nose 34 of which projects beyond the front faces of the bars 24, 25, a sufficient distance to engage 80 the rear end of the band 13 which is in contact therewith. A pin 35, crossing the aperture 32, is engaged by the rear end of the dog 33 when the feeder is retracted, so as to swing its nose back of the band next to be 85 advanced. The feeder now being pushed forward, the band is carried with it. Upon retracting the feeder the dog will be tilted backwardly slightly, its nose sliding over the face of the band next in order. 90

The device is shown for use in connection with a former and holder 36, which may be seated in a suitable aperture 37 formed in the bed 10. This former and holder, while of special construction, does not constitute 95 any part of the present invention. It is provided with a tangential channel 38, for receiving the band,—this channel, when the holder and former is in place, being in line with the advancing band. As the feeder is 100 pushed forward by the operator, the band enters the channel 38 and follows the interior surface of the former, and is there securely held in position to be fitted to the article to which it is adapted to be attached. 105

In use the follower 14 is first retracted, a quantity of bands are introduced in front of it, and the latch 22 being released pressure

- is applied by the weights 20, or other equivalent means, to force the mass of bands forwardly against the faces of the bars 24, 25. While the bands will normally rest evenly upon the upper surface of the bed, care is not required to insure accuracy in this regard as they are positively forced downwardly upon the bed by the lips 26.
- The bands will, of course, be given such shape as may be required. There is shown a band having a tag 39 at one end, by means of which it may be grasped for the purpose of stripping it from the form to which it shall subsequently be attached. The band is also shown as having its forward end 40 beveled, this form conveniently serving to engage an overhanging lip 41 of one of the guide elements 12, the tag 39 being engaged by a similar lip on the other guide element.
- 20 I claim as my invention—
1. In a band feeding device, in combination, a suitable bed upon which a quantity of bands may rest on edge, ways between which the mass of bands may be advanced laterally, a follower for advancing the mass

Copies of this patent may be obtained for five cents each, by addressing the "Commissioner of Patents, Washington, D. C."

of bands, a face plate against which the bands may be pressed and along which they may be separately moved longitudinally, a reciprocating feeder having a pivoted dog engageable with one end of the band bearing against the face plate, a detent for advancing the nose of the dog as the feeder reaches the limit of its retractive movement and means for holding the mass of bands against movement by the friction of the band moved by the feeder.

2. In a band feeding device, in combination, a suitable bed upon which a quantity of bands may rest on edge, ways between which the mass of bands may be advanced laterally, such ways having overlapping lips, a follower for advancing the mass of bands, a face plate against which the bands may be pressed and along which they may be separately moved longitudinally, and a reciprocating feeder having a dog engageable with one end of the band bearing against the face plate.

WILLIAM S. HAMM.
